UNITED STATES PATENT OFFICE.

VICTOR J. DIEFENDERFER, OF SOUTH BETHLEHEM, PENNSYLVANIA, ASSIGNOR TO
VICTOR ENGINEERING COMPANY, LIMITED, OF ALLENTOWN, PENNSYLVANIA.

SPEED-GOVERNOR.

1,142,803.

Specification of Letters Patent. Patented June 15, 1915.

Application filed September 14, 1914. Serial No. 861,572.

To all whom it may concern:

Be it known that I, VICTOR J. DIEFENDERFER, a citizen of the United States, residing in South Bethlehem, in the county of 5 Northampton and State of Pennsylvania, have invented certain new and useful Improvements in Speed-Governors, of which the following is a specification.

This invention relates to governors for 10 regulating the speed of steam engines and other prime movers and machines, the speed of which may vary and which require mechanism for so controlling them as to maintain as nearly as possible a uniform speed.

15 It relates particularly to governors in which balls or weights contained within a casing are pivotally connected with an upright shaft and are rotated with the shaft and casing, while at the same time moving 20 outward from the axis of the shaft and rising while in contact with the casing causing the latter to rise and fall, and by suitable connections, to operate mechanism which controls the action of the engine valves or 25 other suitable devices for regulating the engine speed.

According to this invention I provide a 30 casing within which are contained centrifugally operated balls in contact with the upper and lower walls of the casing and connected in a new way to a vertical governor shaft passing through the casing by arms of such construction as to allow the 35 balls to rise and fall to the desired extent to give the required movement to the controlling mechanism.

My improvements are shown in the accompanying drawings, in which,

Figure 1 shows a vertical central section 40 through a speed governor embodying my invention with some parts shown in elevation. Fig. 2 is a view on an enlarged scale and in transverse section on the line 2—2 of Fig. 1. Fig. 3 is a top plan view on an enlarged scale with the top of the casing removed. Fig. 4 shows a transverse section on the line 4—4 of Fig. 1. Fig. 5 is a perspective view of one of the end members of one of the governor weights. Fig. 6 is a 45 perspective view of one of the governor arms. Fig. 7 is a perspective view of the middle member of one of the governor weights. Fig. 8 shows an end elevation thereof. 50 The casing comprises a body portion A and a removable top or cover A' held in place by screws a⁵. The body portion A is circular in cross section having a bottom wall a' and a vertical side wall a². The casing is formed with a boss or hub a³ through 55 which extends the governor shaft B and to which it is connected at s' in such manner that it rotates therewith, but may move vertically thereon. The top A' is provided with a dome a⁴ having a cavity or chamber a to accommodate certain parts of the mechanism hereinafter referred to. The upper end of the governor shaft B extends through the dome a⁴ and is connected therewith by a feather and groove s, as shown, so that the 60 top A' revolves with the shaft B but may move vertically thereon. 65 Within the casing are arranged the governor balls or weights C. These may be of any suitable construction, but are preferably 70 made in sections as shown. Each governor weight, as illustrated, comprises a middle part c and two side parts c'. The three parts c, c' are placed side by side by side and secured to arms D pivotally connected 75 with the governor shaft B. Each weight is connected with the governor shaft by two links D, the upper ends of which are pivotally connected with a trunnion block E bolted to the shaft B at e. The block E is formed with trunnions f and the arms D are held in place on the trunnions by washers f' and bolts or screws f². The weight sections are preferably given the shape 80 shown in the drawings and are grooved at c² to receive the lower ends of the arms D. The end parts c' have their outer portions 85 curved as shown to correspond with the curvature of the casing and the middle part c has its inner part cut away as illustrated 90 to enable it to come close to the governor shaft B when the governor is at rest or is running at low speed. The parts c, c' are held in place by bolts G, which also pass 95 through the outer ends of the arms D. The 100 governor arms D are each bent at d to form an inner part d' which, when the governor is at rest, is substantially parallel with the axis of the shaft B and an outer part d² which is inclined relatively to the inner 105 part. This construction is of importance because when the weights are moved outward and upward by centrifugal force they are enabled to rise to a greater extent before the arms D come in contact with the 110

55 The casing comprises a body portion A

top of the casing and thus a wider range of movement is afforded. If the arms were straight or radial they would soon come in contact with the casing and the range of movement would be thus limited.

By the use of the bent or angular governor arms I am enabled to obtain a compact arrangement, but one which gives all the necessary range of movement.

10 The governor shaft B extends vertically through a hollow standard H resting on a gear casing I and power is transmitted to the shaft by means of pinions i, i' operated by a shaft J connected with the engine or prime mover in any suitable way.

15 The boss a^3 of the casing carries a sleeve nut L and a flanged ring K. The nut is provided with a flange l and between said flange and the top of the sleeve nut is interposed a collar T. The ring K and nut L revolve with the casing, but the collar T does not revolve therewith but is pivotally connected at m with levers M jointed to a bracket N attached to the standard G and also provided 20 with means O for connecting them with the parts to be governed. The construction is such that as the casing rises and falls corresponding movements will be given to the levers M and to the connecting means O.

25 30 In order to provide means for adjusting the governor when speed variation is desired, I may provide a spring P which surrounds the standard H and rests on a collar Q surrounding the standard and connected by links R with a collar T. The standard is threaded as shown at d and receives an adjusting nut S by means of which the tension of the spring may be varied and the sensitivity of the governor adjusted. I would 35 say, however, that I do not herein claim the special mechanism shown for communicating power to the governor shaft or of adjusting the governor, as my invention, so far as herein claimed, relates to the manner of arranging and operating the governor weights 40 or balls within the casing.

45 I claim as my invention:

1. A speed governor, comprising a vertical driven shaft, a casing mounted to move ver-

50 tically thereon and to revolve therewith, governor weights confined within the casing on opposite sides of the shaft and engaging the inner surface of the top wall of said casing, and swinging arms pivotally connected with the weights and pivotally connected with the 55 shaft in a plane above the inner surface of the top wall of the casing engaged by the weights.

2. A speed governor, comprising a vertical driven shaft, a casing mounted to move 60 vertically thereon and to revolve therewith and the top of which is dome-shaped and provided with a chamber, governor weights confined within the casing on opposite sides of the shafts and engaging at all times the 65 inner surface of the top wall of the casing, and swinging arms pivotally connected with the shaft in said chamber above the inner surface of the top wall of the casing, and also pivoted to said weights for the purpose 70 specified.

3. A speed governor, comprising a vertical driven shaft, a casing mounted to move vertically thereon and to revolve therewith, 75 governor weights within the casing on opposite sides of the shaft and engaging the inner surface of the top wall thereof, and swinging arms pivotally connected with the shaft above said inner surface, said arms having inner portions connected with the shaft and 80 outer portions connected with the weights arranged at an angle to said inner portions.

4. A speed governor, comprising a vertical driven shaft, a casing mounted to move vertically thereon and to revolve therewith, 85 governor weights made in sections within the casing on opposite sides of the shaft and engaging the top wall of said casing, and swinging arms pivotally connected with the shaft and secured between the sections of 90 the weights.

In testimony whereof, I have hereunto subscribed my name.

VICTOR J. DIEFENDERFER.
